(57) **CLAIM**

The ornamental design for a transcutaneous electrical nerve stimulation or tens device, as shown and described.

DESCRIPTION

FIG. 1 is a side view of a transcutaneous electrical nerve stimulation or tens device;

FIG. 2 is a bottom view thereof;

FIG. 3 is a front view thereof;

FIG. 4 is a top view thereof;

FIG. 5 is a side view thereof; and,

FIG. 6 is a back view thereof.
